UNITED STATES PATENT OFFICE.

MILES OVERHOLT, OF SAN FRANCISCO, CALIFORNIA.

HAIRBRUSH.

Application filed November 30, 1927. Serial No. 236,664.

This invention relates to toilet articles, and more especially to a hairbrush having means for retaining a set of toilet articles in the back thereof.

5 An object of the invention is to provide a toilet kit comprising in combination a hairbrush, mirror, and carrying case for other toilet articles.

With the foregoing and other objects in view which will be made manifest in the following detailed description and specifically pointed out in the appended claim, reference is had to the accompanying drawings for an illustrative embodiment of the invention, wherein:

10 Figure 1 is a plan view showing the back of the hairbrush of my invention. Parts are broken away to better reveal the nature of the invention.

15 Fig. 2 is a longitudinal sectional view, the plane of section being indicated by the line 2-2 of Figure 1.

Fig. 3 is a transverse sectional view, the plane of section being indicated by the line 25 3-3 of Figure 1.

Referring to the accompanying drawings wherein similar reference characters designate similar parts throughout, the hairbrush of my invention comprises a back 1 having a handle 2. One face 3 of the back 1 is provided with bristles 4 of the conventional type to provide a hairbrush. The other face 6 is extended to increase the thickness of the back 1 so as to accommodate a large recess 7 within which may be disposed a plurality of toilet articles such as a toothbrush 8, tube of toothpaste 9, tube of shaving cream 11, folding comb 12, and shaving brush 13. The assortment however, of toilet articles is optional, and any combination desired may be accommodated. In order to retain the toilet articles in place, the bottom 14 of the recess 7 may be provided

45 with a plurality of grooves 16, each groove being of such size and shape as to frictionally engage the article intended to be placed therein to releasably retain the article in place. A large groove 17 may be provided if desired, within which a small safety razor may be carried. A lining 18 may be adhesively secured within the recess 7 and grooves 16 and 17. This lining may be of 50 felt, velvet, or other cushioning material which will not only add to the attractiveness of the hairbrush, but aid in retaining 55 the toilet articles in place.

A groove 21 is provided adjacent the top of the recess 7, within which a mirror 22 is slideable. This mirror may be a piece of steel suitably polished to provide a reflecting surface, and is provided at one end with a rolled flange 23 to facilitate its removal from the hairbrush. At one end of the recess 7, the groove 21 extends through the extended back 6 to permit the mirror 22 to slide therethrough.

It will be understood that various changes in the details of construction may be made without departing from the spirit or scope of the invention as defined by the 70 appended claim.

I claim:

A hairbrush comprising a back having a recess in one face thereof, bristles extending from the other face, grooves in the bottom of said recess for retaining toilet articles, said grooves being shaped to frictionally engage their respective articles, a cushion lining for said recess and grooves, and a mirror slideable within a groove adjacent the 75 top of said recess, to provide a closure therefor.

In testimony whereof I have signed my name to this specification.

MILES OVERHOLT.
